FIG. 4.

UNITED STATES PATENT OFFICE.

CONRAD SCHÜTZ, OF PHILADELPHIA, PENNSYLVANIA, ASSIGNOR OF ONE-HALF TO
CHARLES B. STRETCH, JR., OF PHILADELPHIA, PENNSYLVANIA.

SEWING-MACHINE.

No. 866,689.

Specification of Letters Patent.

Patented Sept. 24, 1907.

Application filed June 8, 1906. Serial No. 320,711.

To all whom it may concern:

Be it known that I, CONRAD SCHÜTZ, a citizen of the United States, residing at Philadelphia, in the county of Philadelphia and State of Pennsylvania, have invented certain Improvements in Sewing-Machines, of which the following is a specification.

This invention is a sewing machine particularly adapted for folding and stitching tape, ribbon or the like in the manufacture of lace, edgings, trimmings or the like, and its main purpose is to provide improved product and improved means for carrying and feeding the material to be folded and stitched, with a view to increasing the capacity of machines of this character, saving material and reducing the number of operatives required.

In the accompanying drawings, Figure 1 represents a perspective view of a sewing machine with my improvements attached thereto; Fig. 2 is a sectional view thereof taken transversely to the arm of the machine; Fig. 3 is a plan view of the clutch mechanism for holding the forming device; Fig. 4 is a sectional view of the mechanism taken parallel to the arm of the machine; Fig. 5 is a bottom view in partial section of the upper feeding mechanism, and Fig. 6 is a sectional elevation 25 of part of the lower feeding mechanism.

In practicing the invention, there is suitably employed a usual form of sewing machine comprising the frame 1 having journaled in its base 2 the crank shaft 3, which operates the shuttle mechanisms 4, and journaled on its arm 5 the crank shaft 6, which is rocked by the shaft 3 through the connecting rod 7, the shaft 6 being connected with and reciprocating the needle bars 8 in the head 9 and operating the needles 10 fixed to the respective bars.

In the improvements a worm 11 is placed on the shaft 3 and engages a worm wheel 12 fixed to a shaft 13, which has a gear wheel 14 fixed thereon and is journaled in a bearing 15 on a bracket 16 carried by the frame. The gear wheel 14 engages a gear wheel 17 which is fixed to a shaft 18, the latter being journaled in bearings 19 and 20 carried by the bracket, and on the opposite ends of this shaft are fixed the gear wheels 21 and 22.

In a bearing 23 on the bracket 16 is journaled a hollow shaft 24 having fixed to the top thereof a gear wheel 25 engaged and revolved by the gear wheel 22, the shaft having fixed thereto and revolving a yoke 26 in which is journaled the spool 27 for carrying the strip of material 28 to be folded.

Bearings 29 fixed to the lower end of the shaft 24 have journaled therein the feed roller 30 which coacts with the feed roller 31 journaled in a shoe 32, the latter being movable with reference to the bearings 29 under control of an adjusting screw 33 set in the shoe 32 and bear-

ing against a cross piece 34, having the plungers 35 in the springs 36 which are supported in the sockets 37 of the bearings 29.

A beveled pinion 38 is fixed to the roller 30, which it revolves through its engagement with the beveled pinion 39 fixed to the bearing 23, the material being drawn thus by the rollers between which it passes from the spool.

In the bearing 40 on the bracket 16 is journaled a sleeve 41 which is revolved therein and about the stationary shaft 42 by the gear wheel 21 meshing with a gear wheel 43 fixed to the sleeve.

The shaft 42 and the former 44 fixed thereto are held stationary by a clutch mechanism comprising the pins 45 adapted to engage the sockets 46 in opposite sides of the top of the shaft, these sockets being capped by a disk 47 secured to the shaft and engaging the pins. The pins are carried by the arms 48 and 49 of levers 50 and 51 which oscillate on the bearings 52 and 53 and are drawn together by the coiled spring 54 connected to them, the levers being guided in their movements by a plate 55 fixed to the bearing 40. A cam 56 fixed to and revolved by the sleeve 41 acts upon the arms 48 and 49 at diametrically opposite points to withdraw the pins 45 alternately, the one holding the shaft 42 while the other is drawn back to permit the passage of the tape 28 as it is carried through the way 57 in the revolving sleeve 41 and the eye 58 of the finger 59 fixed to the sleeve.

The tape, having been folded upon the stationary former 44 by the revolving finger 59, is carried from the former under the needles 10 and the presser foot 60 and stitched to the parallel tapes 61 drawn through the passage 62, the stitched fabric being engaged by the rollers 63 and 64 which draw the materials under the needles and presser foot. The roller 63 has journals 65 carried by the hangers 66 which are pivoted to a bifurcated lever 67 fulcrumed on the uprights 68, the roller being pressed down by springs 69. The roller 64, journaled in the bearing 70, has a gear wheel 71 fixed thereto which is driven, to effect a positive feed, by a gear wheel 72 on a shaft 73 carried by a bearing 74. Fixed to the wheel 72 are the disks 75 and 76, the latter having the flange 77 thereon. The surface of the disk 75 is engaged by a brake band 78 having one end connected with the frame member 79 and the other connected with the spring 80 supported by the frame member 81. Engaging the disk 76 is a clutching piece 82 having in the outer end thereof a notch 83 fitting the flange 77, the inner end being fulcrumed in a notch 84 in a hub 85 which is sleeved on the shaft 73 and movable relatively to the disk 76.

The hub has projecting therefrom an arm 86, which is connected by a spring 87 with the clutching member

and an arm 88 which is connected by a link 89 with a lever 90 rocking on the fulcrum 91, the lever being connected with and operated by the usual feeding mechanism 92. As this mechanism is oscillated the 5 movement of the hub in the direction of the arrow moves the inner end of the clutching member so as to throw it out of the radial line and cause it to grip the flange of the disk 76 which with the gear wheel 72 is turned forward by the engagement of the inner end 10 of the clutch member in its seat in the hub. In the movement of the hub in the reverse direction, the spring 87, put under tension by the movement of the arm 86, draws the clutching member back freely upon the disk which is held against rearward movement by 15 the brake band.

It will now be understood that the revolving main shaft 3, acting through the connections described, simultaneously operates the rollers 30 and 31 to draw the material 28 from the spool 27, revolves the shaft 24 20 and the sleeve 41 to wind the material upon former 44, reciprocates the feeding mechanism 92 to draw the material under the needle 10 and revolves the rollers 63 and 64 through their connections with the feed mechanism to carry away the finished product.

25 Having described my invention I claim:—

1. In combination with sewing mechanism, a material holder, a revolving device with a passage therethrough for revolving said holder and passing material therefrom, rolls carried by said revolving device for drawing material therethrough, a stationary former, and mechanism whereby said material is carried to and wound around said former.
2. In combination with sewing mechanism, a former, a device to which said former is fixed, a clutch mechanism 35 having means which alternate in engaging and disengaging said device to hold it and permit material to be revolved about said device, and means for winding said material around said former.
3. In combination with sewing mechanism, a stationary 40 former, a shaft for supporting said former, a pair of devices adapted for engaging said shaft, and a sleeve revo-

luble on said shaft and having means for withdrawing said devices alternately from their engagements with said shaft.

4. In combination with sewing mechanism, a stationary former, a device fixed to and holding said former, a pair of reciprocating pins adapted for engaging said device and a revolving cam for withdrawing said pins alternately from their engagements.

5. In combination with sewing mechanism, a bearing, a shaft with a passage therein for a strip of material, said shaft being revolvable in said bearing, means for revolving said shaft, a pair of rolls carried by said shaft for drawing material through said passage, and mechanism whereby the revolution of said shaft revolves one of said rolls.

6. In combination with sewing mechanism, a revolvable member having means for passing a strip of material carried thereby, a stationary former, a second revolvable member having means for passing said strip of material, and mechanism for holding said former, said mechanism being acted upon by said second revolving device to permit the 60 passage of said material.

7. In combination with sewing mechanism, a bearing, a shaft revolvable in said bearing and having means for passing material carried thereby, a gear wheel fixed to said bearing, a revolvable gear wheel and rollers carried by said shaft, said gear wheels engaging to operate said rollers, a gear wheel fixed to said shaft, a revolvable shaft and a gear wheel thereon engaging said last named gear wheel, and means for revolving said last named shaft and operating said sewing mechanisms together.

8. In combination with sewing mechanism, a main shaft having a worm thereon, a gear train comprising a worm wheel operated by the worm of said main shaft, a shaft connected with and revolved by said gear train and having means for passing materials carried thereby, a sleeve 75 having means for passing material, said sleeve being connected with and revolved by said gear train, a former, a shaft within said sleeve for supporting said former, a clutch mechanism for holding said shaft, and a cam operated by said sleeve to act upon said clutch mechanism so as to permit said sleeve to revolve said material.

In testimony whereof I have hereunto set my name this 7th day of June, 1906, in the presence of the subscribing witnesses.

CONRAD SCHÜTZ.
